O. H. STYLES.
CIGARETTE CASE.
FILED DEC. 12, 1921.

UNITED STATES PATENT OFFICE.

OTTO H. STYLES, OF TOLEDO, OHIO.

CIGARETTE CASE.

Application filed December 12, 1921. Serial No. 521,616.

To all whom it may concern:

Be it known that I, OTTO H. STYLES, a citizen of the United States, and a resident of Toledo, in the county of Lucas and State 5 of Ohio, have made an invention appertaining to a Cigarette Case; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention has for its object to provide a case wherein cigarettes, soda fountain straws, matches or the like may be easily dropped or dispensed one by one from the case and yet wherein the articles will be held 20 in position when the case is closed to prevent undue shaking of the articles or displacement in the case. The invention has for its object other features and advantages that will appear from the following description and upon examination of the drawings forming a part hereof.

25 The invention may be contained in cases of different forms, and to illustrate a practical application of the invention I have selected a cigarette case as an example of such constructions and shall describe it hereinafter. The construction selected for purposes of illustration is shown in the accompanying drawings.

30 Figure 1 of the drawings illustrates a top view of the case, a part being shown broken away. Fig. 2 illustrates a side view of the case. Fig. 3 illustrates a side view of the case when the case is open for the purpose of 35 removing a cigarette. Fig. 4 is a sectional view taken on the line 4-4 indicated in Fig. 1. Fig. 5 is a sectional view taken on the line 5-5 also indicated in Fig. 1.

40 In the figures is a shell which is closed, except for the opening 2 formed at one end and at the top of the shell. The top 3 of the shell may be hinged on the rod 4 and may be secured in closed position by the raised knobs 5 located on the sides of the 45 body portion of the shell 1 that registers with openings formed in the sides of the cover 3, or the cover 3 may be permanently secured, as by solder or spot welding, and constitute a permanent part of the body portion 50 of the shell 1, or it may be formed from

the sheet from which the body portion 1 is formed, and thus be an integral part of the shell 1. The top 3 of the shell is provided with a plurality of slots 6 in which are located springs 7 that are secured preferably to the underside of the top and are bellied upwards so as to extend to the outside of the shell, both ends thus being located within the shell. Alternate springs are preferably secured near the opposite ends of the shell so that the free ends of alternate springs will likewise extend towards opposite ends of the shell and the free ends may be depressed by pressure on the bellied portions of the springs.

55 The case cover 8 is provided with a top portion 9 and side portions 10. The side portions 10 extend over the sides of the shell 1 and is provided with a suitable finger engaging means, such as the raised portions 11, whereby the top of the case 8 may be held in hand by pressure of the thumb and finger of the user upon the sides 10. The cover of the case is connected to the shell by rods 12 and 13. The rods 12 may be 60 formed integral with the springs 14 that surround the ends of the rod 4. The rods 12 and 13 have a length that is greater than the thickness of the cigarette case. They are pivotally connected to the shell and to the 65 cover 8 and are located in parallel relation so that, notwithstanding the movements of the shell or cover relative to the other they will be maintained in substantially parallel relation. The springs 14 operate to yieldingly close the cover over the opening 2 of the shell and at the same time to cause the cover to press against the bellied portions of the springs 7 and depress the free ends of the springs into the shell.

70 Cigarettes may be inserted through the opening 2 when the cover is raised by movement of the shell relative to the cover and thus the case may be filled with cigarettes and when the cover 8 is lowered by return 75 movement of the shell relative to the cover the springs 7 will be depressed and hold the cigarettes in position except the one opposite the opening 2 and so as to prevent them from turning endwise toward the opening 2 by 80 shaking of the case, such as it is subject to when being carried in the user's pocket.

85 The end of the shell is provided with a plate 15 that is pivotally connected to the shell 1 by means of the pintle 16. The pin- 90

90

95

100

105

110

tle 16 is located at the edge of the opening 2 that is nearer to the end of the shell 1. A spring 17 operates to swing the plate 15 and the free edge thereof towards the other edge 5 of the opening 2. The ends of the plate 15 are provided with the pins 18 that are located in the slots 19 formed in the sides of the shell 1, and thus the movement of the plate 15 is limited by the pins 18 and the 10 slots 19. The ends of the plate 15 are also provided with cam members or flanges 20 that are formed integral with the plate 15 and which are located at right angles to the plate 15 and at the ends thereof. The flanges 15 20 extend outward through the opening 2 and so as to be engaged by the underside of the cover 8 when the cover is closed by the operation of the spring 14. The flanges or 25 cam members 20 extend from the plate 15 a distance sufficient to cause the plate 15 to be depressed substantially to bottom of the shell 1 when the cover 8 is closed, and the pin 18 and the slot 19 are so located as to permit the free edge of the plate 15 to move by the 30 operation of the springs 17 to substantially the center of the shell 1. When, therefore, the case is held in a vertical position the lowermost cigarette, which is free from the springs 7, will pass down over the plate 15 and be placed intermediate the plate 15 and the top of the cover 8, and when the shell 1 is depressed relative to the cover so as to uncover the opening 2 the lowermost cigarette will drop from the case, but at the same time 35 the plate 15 will be swung to its mid-point position by the operation of the spring 17 and its free edge will engage the succeeding cigarette so as to hold the cigarettes in the case which have been dropped towards the lower end since the springs 7 have been released by the movement of the top of the 40 cover 8 from the shell 1. When, therefore, the cover is closed after the removal of the cigarette the springs 7 and the plate 15 will again be depressed and if another cigarette 45 is desired the depression of the shell by the forefinger of the user while the cover is being held between the thumb and the other fingers, will release another cigarette while the others have dropped down and are held in position by the edge of the plate 15.

If desired, a moistening pad 21 may be located in the end of the shell 1 and a portion 22 of the plate 15 may be bent inward 55 so as to prevent the pad or sponge 21 from becoming displaced from the end of the shell. The pad 21 may be moistened with water and thus the tobacco of the cigarettes may be contained in an atmosphere of suitable humidity.

I claim:

1. In a case for cigarettes and the like, a shell and a cover, a member operated by the cover for releasing a cigarette from the 65 shell and engaging a second cigarette in the

shell when the cover is opened, and a second member for releasing a third cigarette in the shell.

2. In a case for cigarettes and the like, a shell and a cover for the shell, a spring member operated by the cover for engaging the cigarettes in the shell when the cover is closed and for releasing the cigarettes when the cover is opened. 70

3. In a case for cigarettes and the like, a shell and a cover, springs having bellied portions and operated by the pressure of the cover on the bellied portions to depress the springs for engaging the cigarettes when the cover is closed and for releasing the cigarettes when the cover is opened. 75 80

4. In a case for cigarettes and the like, a shell and a cover for the shell, a pivoted member located in the shell and operated by the cover to remove a cigarette from the shell. 85

5. In a case for cigarettes and the like, a cover and a shell, a plate pivoted to the shell and operated by the cover for releasing a cigarette from the shell and for engaging the adjoining cigarette. 90

6. In a case for cigarettes and the like, a cover and a shell, a spring-pressed plate pivoted to the shell and operated by the cover, means for limiting the movements of the plate to release a cigarette and engage the adjoining cigarette in the shell. 95

7. In a case for cigarettes and the like, a cover and a shell, a plate pivoted to the shell and operated by the cover for releasing a cigarette from the shell and for engaging the adjoining cigarette, a spring-pressed member operated by the cover for engaging cigarettes contained in the shell when the cover is closed and releasing the cigarettes when the cover is opened. 100 105

8. In a case for cigarettes and the like, a cover and a shell, a plate pivoted to the shell and operated by the cover for releasing a cigarette from the shell and for engaging the adjoining cigarette, a spring-pressed member operated by the cover for engaging cigarettes contained in the shell when the cover is closed and releasing the cigarettes when the cover is opened, a moistening pad located in the shell. 110 115

9. In a case for cigarettes and the like, a cover and a shell, a plate pivoted to the shell and operated by the cover for releasing a cigarette from the shell and for engaging the adjoining cigarette, a spring-pressed member operated by the cover for engaging cigarettes contained in the shell when the cover is closed and releasing the cigarettes when the cover is opened, a moistening pad located in the shell, means for retaining the moistening pad in one end of the shell. 120 125

10. In a case for cigarettes and the like, a shell, a cover, rods connecting the ends of 130

- the cover with the ends of the shell to maintain the cover in substantially parallel relation to the shell notwithstanding the movements of the cover relative to the shell, a 5 spring-pressed plate pivotally connected to the shell and controlled by the cover, means for limiting the movement of the plate for the ejection of successive cigarettes upon each opening of the cover.
- 10 11. In a case for cigarettes and the like, a shell, a cover, rods connecting the ends of the cover with the ends of the shell to maintain the cover in substantially parallel relation to the shell notwithstanding the movements of the cover relative to the shell, a 15 spring-pressed plate pivotally connected to the shell and controlled by the cover, means for limiting the movement of the plate for the ejection of successive cigarettes upon each opening of the cover, a plurality of 20 springs having bellied portions extending through the shell and operated by the cover to release the cigarettes in the shell when the cover is opened and to engage the cigarettes in the shell when the cover is closed. 25
12. In a case for cigarettes and the like, a shell, a cover, rods connecting the ends of the cover with the ends of the shell to maintain the cover in substantially parallel relation to the shell notwithstanding the movements of the cover relative to the shell, a 30 spring-pressed plate pivotally connected to the shell and controlled by the cover, means for limiting the movement of the plate for the ejection of successive cigarettes upon each opening of the cover, a plurality of springs having bellied portions extending through the shell and operated by the cover to release the cigarettes in the shell when the cover is opened and to engage the cigarettes in the shell when the cover is closed, a moistening pad located in one end of the shell. 35
- 40

In testimony whereof, I have hereunto signed my name to this specification.

OTTO H. STYLES.
